UNITED STATES PATENT OFFICE.

JOHN M. DOWNS, OF SAVANNAH, GEORGIA.

APPARATUS FOR HANDLING ELECTRIC CONNECTOR OR TAPPING DEVICES.

1,128,956.

Specification of Letters Patent. Patented Feb. 16, 1915.

Application filed March 9, 1914. Serial No. 823,382.

To all whom it may concern:

Be it known that I, JOHN M. Downs, a citizen of the United States, residing at Savannah, in the county of Chatham and 5 State of Georgia, have invented certain new and useful Improvements in Apparatus for Handling Electric Connector or Tapping Devices, of which the following is a specification.

10 My invention relates to an apparatus for placing a spring connector upon a high power electric feed wire and for removing the same therefrom.

An important object of the invention is to 15 provide an apparatus of the above mentioned character, which will render it safe to place the spring connector upon a high power feed wire and remove the same therefrom, and at the same time enabling such 20 operation to be performed in a convenient and expeditious manner.

A further object of my invention is to 25 provide apparatus of the above mentioned character, which is simple in construction, cheap to manufacture, strong, and durable.

Other objects and advantages of the invention will be apparent during the course 30 of the following description.

In the accompanying drawings forming a part of this specification and in which like numerals are employed to designate like 35 parts throughout the same, Figure 1 is a side elevation of the complete apparatus, Fig. 2 is an edge elevation of the same, and, Fig. 3 is a horizontal section taken on line 3-3 of Fig. 1.

In the drawings, wherein is illustrated a preferred embodiment of my invention, the numeral 4 designates a handle, constituting 40 the body portion of the apparatus, the same being formed of wood or any other suitable insulating material. This handle carries a clamp or vise 5, comprising a relatively stationary jaw 6, formed upon one end of 45 the handle 4.

The numeral 7 designates a co-acting jaw, which is pivoted to the handle 4, as shown at 8. The jaw 7 is preferably formed of wood or any other suitable insulating material. The jaw 7 is swung outwardly, when 50 released, by a suitably stiff coil spring 7', disposed between the same and the relatively stationary jaw 6. The jaw 6 is provided with a transverse opening 9, receiving 55 therethrough a transverse bar 10, provided at one end with an enlarged head 11. The

outer end of the transverse bar 10 passes through a relatively large transverse opening 11' formed in the co-acting jaw 7, the opening 11' being sufficiently large to permit of the oscillatory movement of the jaw 7. The outer end of the transverse bar 10 is forked to receive an operating cam 12, pivoted thereto by means of a transverse bolt 13 or the like. This cam is formed upon 60 a vertically swinging lever or arm 14, as shown. Pivotedly connected with the cam 12, as shown at 15, is a pawl-bell-crank-lever 15' adapted to engage and disengage teeth 16 formed upon the transverse bar 10. The 65 function of this pawl and the teeth 16 is to lock the lever 14 against upward movement, such lever being swung downwardly to force the pivoted jaw 7 toward the relatively stationary jaw 6. The pawl-bell-crank-lever 15' is urged toward the teeth 16 70 by a spring 17. Attached to the outer end of the lever 14 is a cord 18 or the like extending downwardly adjacent the handle 4. Attached to the free end of the pawl-bell-crank-lever 15' is a cord 19 or the like extending downwardly adjacent the handle 4. 75

Disposed upon the opposite side of the jaw 6 with relation to the pivoted jaw 7 are a plurality of spaced approximately U-shaped brackets 20, rigidly connected therewith and provided with apertured heads or knuckles 21, receiving therein reciprocatory rods 22. These rods are connected at their lower ends by a transverse approximately 80 U-shaped bracket 23, adapted to move longitudinally of the handle. At their upper ends the reciprocatory rods 22 are off-set 85 laterally and outwardly, providing shoulders 24 and extensions 25. The numeral 26 designates coil springs, surrounding the upper portions of the rods 22 and confined between the upper stationary bracket 20 and the shoulders 24, whereby they serve to normally hold the rods 22 elevated with relation to the jaw 6. 90

The numeral 27 designates an inverted approximately U-shaped removing element or rod, detachably and rigidly connected with the extensions 25 by means of couplings 28 or the like. 95

The numeral 29 designates my improved spring connector to be placed upon and removed from the high power feed wire 30. This spring connector includes spring blades 110 31 and 32, disposed in different planes so that they will engage the opposite sides of

the wire 30. No further detailed description of the spring connector 29 is deemed necessary, as the same is fully shown and described in my copending application for 5 wire connector, filed March 9, 1914, Serial No. 823,381. Connected with the slideable bracket 23 is an attaching element 33, with which is connected a depending cord 34 or the like, extending downwardly adjacent the 10 handle 4.

The operation of the apparatus is as follows: When it is desired to place the spring connector 29 upon the feed wire 30 the lower portion of the connector is disposed 15 between the jaws 6 and 7 of the vise or clamp 5, subsequently to which the arm or lever 14 is swung downwardly to close the jaw 7. The operator by holding the handle 4 may now place the connector 29 upon the 20 wire 30 by an upward longitudinal movement of the same. When the connector 29 is thus placed upon the wire the pawl 15' is moved to release the lever 14, such lever moving upwardly by virtue of the spring 7', 25 whereby the clamp or vise will release the connector 29. When it is desired to remove the connector 29, it is necessary to spread the upper ends of the spring blades 31 and 32. This is accomplished by inserting the 30 horizontal portion of the inverted U-shaped rod 27 between the same, as shown in Fig. 1. The operator now holds the handle 4 stationary and pulls upon the cord 34, whereby the inverted U-shaped rod 27 is moved 35 downwardly to spread the blades of the connector 29. While these blades are thus being spread, the connector is engaged by the vise or clamp, which is pulled downwardly, whereby the connector will readily disengage the wire. 40

It is to be understood that the form of my invention herewith shown and described is to be taken as a preferred example of the same, and that various changes in the shape, 45 size and arrangement of parts may be resorted to without departing from the spirit of the invention or the scope of the subjoined claims.

Having thus described my invention, I 50 claim:—

1. In apparatus of the character described, the combination with a handle formed of insulating material, of a clamp carried by the upper end thereof to temporarily hold 55 a spring connector, means to operate the clamp, and means connected with the handle to engage and laterally spread the blades of the spring connector and movable with relation to the handle.

2. In apparatus of the character described, the combination with a handle formed of insulating material, of means connected therewith to detachably hold a spring connector, and separate means connected with 60 the handle for engaging and laterally

spreading the blades of the spring connector and movable with relation to the handle.

3. In apparatus of the character described, the combination with a handle formed of insulating material and provided with a 70 relatively stationary jaw, of a co-acting jaw pivoted to the handle, means to swing the pivoted jaw outwardly when released, means to move the pivoted jaw to the inner position, and means to lock the jaw in such 75 position.

4. In apparatus of the character described, the combination with a handle formed of insulating material and provided with a jaw, of a co-acting jaw pivoted to the handle, a 80 spring arranged between the co-acting jaws to automatically swing the pivoted jaw to the outer position when released, a transverse bar connected with the relatively stationary jaw and passing through a transverse opening formed through the pivoted jaw, a lever provided with a cam pivotally connected with the transverse bar and slidably engaging the pivoted jaw to swing the same inwardly, teeth formed upon the outer 85 end of the transverse bar, and a pawl pivoted to the lever and adapted to engage the teeth.

5. In apparatus of the character described, the combination with a handle formed of 95 insulating material, of a spring connector removing element having a portion adapted to pass between the blades of the connector to spread the same, and reciprocatory operating means mounted upon the handle 100 and connected with the spring connector removing element.

6. In apparatus of the character described, the combination with a device for spreading the blades of a spring connector, of means 105 movable with relation to the handle to simultaneously grip the spring connector while the blades are thus being spread and remove the same from a wire.

7. In apparatus of the character described, the combination with a handle, of a rod mounted thereon to reciprocate with relation thereto, a spreading element attached to the reciprocating rod and a holding device secured to the handle and arranged in co-operative relation to the spreading element. 110

8. In apparatus of the character described, the combination with a handle, of a reciprocating rod mounted thereon, a spring to move the rod in one direction, means to move the rod in an opposite direction, and a spreading element attached to the rod. 120

9. In apparatus of the character described, the combination with a handle, of a guide bracket mounted thereon, a plurality of reciprocating rods mounted within the guide bracket, springs surrounding the reciprocating rods to move them in one direction, means to move the rods in an opposite direction, and an inverted U-shaped element at- 125 130

tached to the corresponding ends of the rods.

10. In apparatus of the character described, the combination with a handle, of means for holding a spring connector or the like, a device connected with the handle and movable with relation thereto, and adapted to engage with the blade of the spring connector or the like to laterally spread the

same, and means to move the spreading device. 10

In testimony whereof I affix my signature in presence of two witnesses.

JOHN M. DOWNS.
